US00D578386S

(12) **United States Design Patent**
Silvenis et al.

(10) **Patent No.:** **US D578,386 S**
(45) **Date of Patent:** **** Oct. 14, 2008**

(54) **CONTAINER FOR TRANSPORTING A
BLISTER PACKAGE**

473,680 A 4/1892 Saunders et al.
534,070 A 2/1895 Tanner
534,421 A 4/1895 Tanner
537,338 A 4/1895 Jackson
819,574 A 5/1906 Moore

(75) Inventors: **Scott A. Silvenis**, Cleveland, TN (US);
Richard S. Costa, Bedminster, NJ (US);
Hung D. Mach, Fort Lee, NJ (US)

(Continued)

(73) Assignee: **Schering-Plough Healthcare Products,
Inc.**, Memphis, TN (US)

FOREIGN PATENT DOCUMENTS

A portion of the disclosure of this patent document contains material which may be protected by copyright. The copyright owner has no objection to the facsimile reproduction by anyone of the patent document or the patent disclosure, as it appears in the Patent and Trademark Office patent file or records, but reserves all other copyright rights whatsoever.

FIG. 1 is a perspective view of a container for transporting a blister package showing my/our new design.

FIG. 2 is a front view thereof;

FIG. 3 is a left view thereof;

FIG. 4 is a rear view thereof;

FIG. 5 is a right view thereof;

FIG. 6 is a top view thereof; and,

FIG. 7 is a bottom view thereof.

The broken lines in the drawings represent environmental subject matter and form no part of the claimed design.
